CAUTERY HANDLE

Walter A. Arnesen, New York, N. Y.

Application August 15, 1936, Serial No. 96,159

6 Claims. (Cl. 128—303.14)

This invention relates to improvements in handles for surgical instruments and more particularly to improvements in cautery handles.

An object of the present invention is to provide a cautery handle of such construction as to accommodate itself most readily to the grip of a user and at the same time to have incorporated therein novel features and advantages.

Another object of the invention is to provide a cautery handle of such construction as to be capable of holding a cautery electrode in a number of selected relative positions.

Another object of the invention is to provide a cautery handle of such construction as to accommodate a source of light rays therein in position to illuminate the part of the body being treated in any of the relative positions of the cautery electrode.

A further object of the invention is to provide a cautery handle having incorporated therein switch mechanism conveniently operable together with means for locking such switch mechanism in contact closing position.

In carrying out the foregoing and other objects of the invention, a cautery handle is made of some molded material preferably some material having good electric insulating properties. The handle in the preferred form is made of two complementary parts which, when connected together, resemble the handle of a pistol, such form being selected on account of its adaptability to the hand grip of the user. This handle has secured therein electric socket members for receiving the prongs of a cautery electrode. The socket members are so disposed as to retain a cautery electrode in a number of positions, in the present instance, two positions which are substantially at right angles to each other. The handle is also provided with a further cavity in which may be secured a socket member carrying a source of light rays. The further cavity is so positioned relative to the electric sockets that a source of light rays properly held by the handle will direct rays toward the end of an electrode held by the handle. Switch mechanism is provided within the handle and an operating member somewhat resembling a trigger is secured to the handle for actuating such mechanism. Since in practice it is sometimes desirable to use the electrode energized over a considerable period of time, locking means are provided for locking the switch mechanism in contact closing position.

Other features, objects, and advantages of the invention will become apparent by reference to

the following detailed description of the accompanying drawings illustrating the same wherein

Fig. 1 is a side view of a handle embodying the invention and showing an electrode in one of the relative positions. 5

Fig. 2 is an end view of the handle showing the apertures through which the prongs of a cautery electrode may pass to enter the electric sockets, such view being taken substantially on the line 2—2 of Fig. 1. 10

Fig. 3 is a plan view of one of the complementary parts of the handle with internal parts thereof in position.

Fig. 4 is a plan view of the other complementary part of the handle. 15

Fig. 5 is a section substantially taken on the line 5—5 of Fig. 1.

Fig. 6 is a section taken substantially on the line 6—6 of Fig. 1.

Fig. 7 is a view of one of the combined socket 20 and terminal members.

Fig. 8 is a similar view of the other of such members, and

Fig. 9 is a view of the switching locking member. 25

Referring now to the drawings, 10 indicates generally a handle made in accordance with the present invention and comprising complementary members 11 and 12. These members are made of some suitable material preferably a material 30 having good electric insulating properties and also a material capable of being molded in the desired form. In practice it has been found that a phenol condensation product serves admirably in all respects. The two complementary members 35 11 and 12 are held together by means of screws 14 passing through apertures in the member 11 into threaded engagement with the walls of apertures in the member 12. The two members 11 and 12 are provided with cavities 15 and 15' 40 which cooperate to form an opening 16 for the reception of a tubular member 17 having a source of light rays 18 secured in one end thereof. The members 11 and 12 are provided with cavities 45 for the reception of the other parts making up the assembly.

These parts are shown separately in Figs. 7, 8, and 9. The member shown in Fig. 7 comprises a double socket arrangement preferably made from a single piece of metal having good electrical conducting properties. As shown in the drawings, this member comprises a socket 20 made up of two strips of material bent back to form a split substantially tubular sleeve. A second socket 21 of similar construction is connected 50

to the socket 20 by an integral strip 22. Extending from the socket 21 is an elongated contact member 24. This part 24 has a definite shape imparted thereto for reasons to be explained hereinafter. Another element in the construction comprises a socket 25 similar to the sockets 20 and 21 and having a contact extension 26 also of a predetermined configuration. In Fig. 9, a member 30 has been shown, such member 10 having the function of locking switch mechanism in place. A still further element of the assembly comprises a terminal member 32 (Fig. 3).

Referring now to Fig. 3, it will be seen that the member 11 has a cavity therein so shaped 15 that a wall 34 divides part of the cavity into two chambers 35 and 36. These chambers are located in the barrel part 37 of this member. The angular extending part of the cavity is divided by a wall 38. In use, the member shown in Fig. 8 20 is positioned in the cavity with the socket 25 located in the chamber 35. On account of the extra length of socket 25 a clip 39 is positioned partly therearound as shown to impart added resiliency to such socket. The member shown in 25 Fig. 7 is also located in the cavity on the opposite side of the wall 38 with the socket 21 positioned in the chamber 36. When this member has been 30 so positioned, the socket 20 will be located above the socket 25 and spaced a distance therefrom approximately equal to the distance between the 35 sockets 21 and 25. The member 32, as shown in the drawings, has a substantially U-shaped portion 40 which fits around the end of a wall 41 intruding into the cavity of the member 11 with a part of the member 32 positioned between this wall and the end of wall 38. The fit is of 40 such good frictional character as to hold member 32 in place. When the parts are so located, the end of the extension 24 is spaced a slight distance from one end of the member 32.

The two members 11 and 12 are provided with 45 arc shaped openings 45 and 45' which combine to provide a passageway for electrical conductors 46 and 47. One of the conductors 46 is secured to the extension 26 while the other conductor 47 is secured to one end of the member 32. Recesses 50 and 51 extend through the end of the barrel part 37 into communication with the chambers 35 and 36 respectively. These recesses 50 and 51 are so positioned as to be substantially 55 coaxial with the sockets 25 and 21 respectively which are positioned in the two chambers.

The member 12 is likewise provided with cavities to properly register with the cavity of the member 11 and the other elements positioned 60 in this member. Thus, the member 12 has a cavity 52 shaped and positioned to receive the socket 20. A recess 54 is provided in the end of the barrel part 37' of member 12, such recess extending into the chamber 52 and being substantially coaxial with the socket 20 when the 65 two parts 11 and 12 are assembled.

Parts of the front walls of the members 11 and 12 are cut away to provide an opening for the reception of a substantially flat trigger-like 70 switch actuator 55. This member 55 is held in assembly by means of pins 56 extending from the opposite sides thereof and fitting into recesses in the walls of the two parts 11 and 12. When the member 55 is in proper position, one 75 edge thereof bears against the extension 24 as shown in Fig. 3. This extension 24 is preferably of metal having sufficient resiliency so that normally the parts are held in the relation shown in Fig. 3. Since member 55 is mounted for limited pivotal movement, it follows that this mem-

ber can be moved to force extension 24 against a part of the member 32, thereby closing an electrical circuit. The opposite edge of member 55 is shaped as shown at 57 to fit the fingers of a user.

Since it is sometimes desirable to lock the switch mechanism comprising the parts 24 and 32 in circuit closing position, the locking member 30 is slidably mounted in suitable slots in the two parts 11 and 12. The member 30 is provided with a slot 58 into which the offset part 59 of member 30 can fit when member 30 has been moved to circuit closing position. A tab 60 of member 30 extends through an opening 61 provided in the handle by two cooperating recesses in the members 11 and 12. This tab 60 is available for manipulation by the user.

The rear edges of the two members 11 and 12 are cut away to provide a channel 62 which extends from the through opening 16 to the end of the stock portion of the handle. The parts 11 and 12 are provided near the lower end of the stock portion of each thereof with matched recesses 64 and 65 which serve to receive a metal spring clip. The channel 62 serves to receive a cable 66 supplying current to the source of light rays 18 while the clip positioned in the recesses 64 and 65 serves to hold this cable in the recess 62.

Since one of the conductors 46 is in electrical contact with the socket 25, it follows that this 30 socket serves as a common socket for completing a circuit with either of the sockets 20 or 21. These two sockets 20 and 21 are in effect in parallel since the other conductor 47 becomes electrically connected thereto when the extension 35 24 is brought into contact with the terminal 32 to which conductor 47 is attached. In use therefore a cautery electrode having two prongs can be secured to the handle in either one of two positions. If desired, one prong of the electrode 40 can be inserted through opening 50 into the socket 25 while the other prong can be simultaneously inserted through opening 54 into the socket 20. Under these circumstances, the socket 21 is idle. If desired, however, the cautery electrode 45 can be arranged at right angles to this first position by simultaneously inserting the prongs thereof through the openings 50 and 51 into the sockets 25 and 21 respectively.

With an electrode in either one of the two 50 positions, the energizing circuit, therefore, can be closed by moving the trigger-like member 55 rearwardly until extension 24 contacts with terminal 32. If the operation to be performed by the 55 electrode requires any length of time, the trigger member 55 can be locked in contact closing position by manipulation of the locking member 30 through the agency of the tab 60.

If desired, the field of operation can be illuminated by means of the source of light rays 18 60 which is inserted from the rear into the through opening 16, the carrier or socket 17 being moved until the bulb 18 reaches the proper location. It is to be understood, of course, that the extensions 26 and 24 are depressed relative to the arcuate 65 shaped opening 15 so that these parts which are metallic cannot come into contact with the socket 17 which is also metallic. To insure that such contingency cannot arise, the member 12 is provided with fingers 70 and 71 which are adapted 70 to fit in the cavity of member 11 on the opposite sides of the wall 38 at the region indicated by the reference character 38'. These fingers 70 and 71 engage the extensions 26 and 24 respectively 75 substantially at this point so that the respective

sockets are held in proper place in their chambers and the extensions 26 and 24 are held depressed relative to the wall of the arcuate shaped opening 15. In order that the member 17 can be held in place against adventitious removal, a resilient member 75 of some good insulating material such as rubber is positioned in matched recesses in the members 11 and 12. The recesses are so positioned that the member 15 protrudes partially into the through opening 16 so that the surface of the socket member 17 will come into contact therewith.

From the foregoing, it will be apparent that the present device provides a new type of handle 15 for cautery electrodes and the like, which type of handle possesses advantages not present in types heretofore used. The handle initially has been designed to fit most comfortably the hand of the user, hence the shape closely resembling the shape of a part of an automatic pistol. The socket arrangement in the handle makes possible the use of cautery electrodes in either one of two positions, in one of which the plane passing through the two prongs of the electrode is substantially parallel with the top of the barrel part of the handle and in the other of which this plane is at right angles to the top of the barrel portion of the handle. With these two positions available, it will be apparent that one or the other thereof will serve to meet practically any situation arising. Moreover, the special switch arrangement provides an efficient trigger-like contact member which can be easily moved to circuit closing position to energize the electrode in any of its relative positions. Likewise the locking arrangement hereinbefore described makes possible the use of the instrument without maintaining pressure by the operator to keep the switch closed.

43 An additional feature present in this device comprises the arrangement by which the area under treatment is properly illuminated, if desired, at all times. As shown in the drawings, the through opening 16 is inclined relative to the axis of the sockets so that the rays of light directed from the bulb 18 will be focused at a point somewhat in advance of the end of the handle. This point of focus ordinarily will be substantially coincident with the energized tip 50 of the cautery instrument. Of course, the light arrangement can be dispensed with if desired but the presence thereof at all times does not interfere with the use of the instrument since the conductor cable for the source of light rays 55 is seated in a recess in the socket part of the handle and is retained therein by a spring clip.

The handle herein shown possesses a special merit that electrodes can be used in connection therewith in various positions as before explained.

60 For example, if the electrode indicated at 90 (Fig. 1) has a thin flat heating element as shown at 91, it may be desirable to manipulate this element to simulate a cutting action. Under some circumstances it will be desirable to move the cutting element vertically relative to the handle as shown in full lines in Fig. 1, or it may be desirable to move the element horizontally relative to the handle (shown in dotted lines in Fig. 1). In either position the energization of the 65 element is accomplished in the manner before set forth.

While the switch arrangement including the actuator has been described in connection with the preferred form, it is to be understood that other arrangements combining the switch mech-

anism and actuator can be used. The requisites are that the switch and actuator be of such character as to permit closing of the switch by finger control, together with an arrangement in which the switch can be held closed either by sustained finger pressure or by some locking arrangement which obviates the necessity for sustaining finger pressure. Various types of mechanism obviously will accomplish these purposes.

It is to be understood that the invention is capable of modification beyond the embodiment illustrated in view of which any limitations thereupon are to be such only as are set forth in the following claims.

What I claim is:

1. A device of the character described comprising a handle made up of complemental portions secured together, said handle having a plurality of chambers therein, electric sockets in said chambers for the reception of the prongs of a cautery electrode in any one of a plurality of positions relative to said handle, said handle being provided with openings aligned with said sockets for the passage of said prongs, said openings passing through insulating material in front of and shielding said sockets, and means for controlling the supply of electric energy to said sockets.

2. A device of the character described comprising a handle made up of complemental portions secured together, said handle having chambers therein, electric sockets in said chambers for the reception of the prongs of a cautery electrode, a spring contact member movably mounted in said handle for controlling the flow of current to said sockets, a trigger-like contact actuator secured to said handle, and means for locking said trigger-like actuator in engagement with said spring contact and in position closing an electric circuit through a cautery electrode held by said sockets.

3. A device of the character described comprising a handle made up of complemental portions secured together, said handle having chambers therein, electric sockets in said chambers for the reception of the prongs of a cautery electrode, said handle having a through opening therein beneath said chambers and a light bulb carrier removably secured in said through opening.

4. A device of the character described comprising a handle made up of complemental portions secured together, said handle having chambers therein, electric sockets in said chambers for the reception of the prongs of a cautery electrode, said handle having a through opening therein beneath said chambers, a light bulb carrier removably secured in said through opening, said light carrier having conductors connected thereto, said handle having a recess extending downwardly from said through opening along one edge of said handle to receive said conductors.

5. A device of the character described comprising a handle made up of complemental portions secured together, said handle having chambers therein, electric sockets in said chambers for the reception of the prongs of a cautery electrode, said sockets being arranged substantially in triangular relation whereby a cautery electrode can be held in either one of two positions relative to the handle, said handle being provided with openings aligned with said sockets for the passage of said prongs, said openings passing through insulating material in front of and shielding said sockets, a single switch in said handle for controlling the supply of energy to a cautery electrode held in any one of its relative positions,

switch actuator secured to said handle, and means for locking said actuator in switch closing position.

5. A device of the character described comprising a handle made up of complemental portions secured together, said handle having chambers therein, electric sockets in said chambers for the reception of the prongs of a cautery electrode, said sockets being arranged substantially in triangular relation whereby a cautery electrode can

be held in either one of two positions relative to the handle, said handle being provided with a through opening beneath said sockets, and a light bulb carrier removably secured in said through opening, said through opening extending at such inclination as to cause the projection of light rays from a bulb carried thereby toward the remote end of a cautery electrode in any of its relative positions.
